US00D994863S

(12) **United States Design Patent** (10) **Patent No.:** **US D994,863 S**
(45) **Date of Patent:** **** Aug. 8, 2023**

(54) **AIR PURIFIER**

(71) Applicants: **Jeoungmin Lee**, Seoul (KR); **SWIS CO., LTD**, Cheonan-si (KR)

(72) Inventor: **Jeoungmin Lee**, Seoul (KR)

(73) Assignees: **Jeoungmin Lee**, Seoul (KR); **SWIS CO., LTD**, Cheonan-si (KR)

(**) Term: **15 Years**

(21) Appl. No.: **35/513,281**

(22) Filed: **Jun. 29, 2021**

(80) **Hague Agreement Data**

Int. Filing Date: **Jun. 29, 2021**

Int. Reg. No.: **DM/217085**

Int. Reg. Date: **Jun. 29, 2021**

Int. Reg. Pub. Date: **Dec. 31, 2021**

(30) **Foreign Application Priority Data**

Jun. 25, 2021 (KR) 30-2021-0030377

(51) **LOC (14) Cl.** **23-04**

(52) **U.S. Cl.**

USPC **D23/364**; D23/356

(58) **Field of Classification Search**

USPC D23/324-330, 332-342, 351-366, 370, D23/381-382

(57) **CLAIM**

The ornamental design for an air purifier, as shown and described.

DESCRIPTION

1. Air purifier

1.1 : Perspective

1.2 : Front

1.3 : Back

1.4 : Left

1.5 : Right

1.6 : Top

1.7 : Bottom

1.8 : Another perspective view showing the air purifier in a state of use

1.9 : Another perspective view showing the air purifier in a state of use.

The evenly spaced broken lines depict portions of the air purifier that form no part of the claimed design. In reproductions 1.8 and 1.9 the evenly spaced broken lines depict unclaimed environment. In reproduction 1.7 the dot dash dot broken line denotes the boundary of the claim and forms no part thereof.

1 Claim, 9 Drawing Sheets
